(57) **ABSTRACT**

Sports boot including: an inner boot; an exogenous shell, the dimensions of which allow the inner boot to be inserted into or extracted from it, the exogenous shell strengthening the inner boot and allowing it to be attached to a piece of sports equipment. The exogenous shell includes a sole, a forward part of an upper able to pivot with respect to the sole about a first articulation, and a rear part of an upper which is able to pivot with respect to the sole about a second articulation. The sole includes a continuous inner relief pattern having longitudinally-extending ribs separated by longitudinally-extending grooves extending continuously along an entire length of the sole. The inner boot includes a sole with a corresponding relief pattern, so as to position laterally and vertically the inner boot in the exogenous shell.

SPORTS BOOT

FIELD OF THE INVENTION

The present invention relates to the field of sports boots, notably the field of sports boots comprising a rigid shell for skiing, skating etc. The present invention relates in particular to a sports boot with a rigid exogenous shell and a removable inner boot of the touring type.

STATE OF THE ART

Ski boots comprising an inner boot and a rigid exogenous shell are known in the state of the art. The inner boot can be extracted from the exogenous shell for walking more comfortably, or inserted into this shell for skiing. An example of such a boot is described in WO2009/097550.

BRIEF SUMMARY OF THE INVENTION

One of the problems with ski boots with an exogenous shell is the transmission of the forces between the inner boot and the exogenous shell. In fact, the inner boot is generally not fastened to the exogenous shell but can slide or move inside it, which prevents an efficient transmission of forces and compromises the skiing style.

One aim of the present invention is to propose a new sports boot with an improved exogenous shell.

According to the invention, these aims are achieved notably by means of a sports boot comprising:

an inner boot (3);

an exogenous shell (1), whose dimensions allow said inner boot (3) to be inserted into or extracted from it, said exogenous shell strengthening said inner boot and allowing it to be attached to a piece of sports equipment;

said exogenous shell comprising a sole (10) and an upper, said inner boot comprising a pivot protruding on the outer side close to the ankle,

said exogenous shell comprising a housing for accommodating the pivot.

This solution makes it notably possible to integrally unite the inner boot and the exogenous shell at an important point for the transmission of forces notably during ski turns.

The exogenous shell can comprise a forward part of an upper capable of pivoting with respect to the sole around a first articulation and/or a rear part of an upper capable of pivoting with respect to said sole around a second articulation. The inner boot can be inserted into the exogenous shell respectively extracted from the exogenous shell by pivoting the rear part of the upper. Buckles can be provided for holding the forward part of the upper and the rear part of the upper closed and tight one against the other. This construction enables the inner boot to be easily extracted resp. inserted and this inner boot to be held efficiently at the ankle.

The housing for the pivot can be opened respectively closed by pivoting the forward part of the upper and/or the rear part of the upper. One portion of the housing's circumference can be formed by an indentation on the forward part of the upper, and another portion of this housing's circumference can be formed by an indentation on the rear part of the upper. The protruding pivot on the inner boot can comprise an annular groove for accommodating the indentations. This construction enables a rigid connection between the pivot and the housing and an easy uncoupling of these components by simply opening the forward or rear part of the upper.

2

The boot can include a reinforcement around the Achilles tendon that is articulated relative to the sole of the exogenous shell and can be fastened to the rear upper.

According to an independent characteristic of the presence of a pivot and of a housing, the sole of the exogenous shell can comprise holes for evacuating water inside this shell. Advantageously, the exogenous shell comprises a structure that is to a large extent perforated to allow the inner boot to be seen and water to be evacuated.

10 The inner side of this sole can include a relief pattern, for example ribs and grooves, working together with a corresponding pattern under the sole of the inner boot, so as to position laterally and to the required height the inner boot in the exogenous shell. This construction thus affords another rigid fastening point (at least along the axis perpendicular to the foot) between the inner boot and the exogenous shell.

15 The invention also relates to an exogenous shell as described and to an inner boot on its own as described.

20 BRIEF DESCRIPTION OF THE FIGURES

Examples of embodiments of the invention are indicated in the description illustrated by the attached figures, in which:

25 FIG. 1 illustrates a complete ski boot with the inner boot and the closed exogenous shell.

FIG. 2 illustrates an exogenous shell on its own in closed position.

30 FIG. 3 illustrates an exogenous shell on its own with the rear part of the upper being open.

FIG. 4 illustrates an exogenous shell on its own with the rear part and the forward part of the upper being both open.

FIG. 5 illustrates an inner boot on its own, capable of working with the exogenous shell of the preceding figures.

35 FIGS. 6 and 7 illustrate different views of a detail of the fastening of the inner boot to the exogenous shell.

FIG. 8 illustrates a view from below of the sole of the exogenous shell.

40 FIG. 9 illustrates a view from above of the sole of the exogenous shell.

EXAMPLE(S) OF EMBODIMENTS OF THE INVENTION

The illustrated sports boot is a ski boot. The invention could also apply to other types of sports boots, for example skating boots, snowboard boots etc.

The sports boot illustrated in FIG. 1 comprises an inner boot 3, illustrated in more detail in FIG. 5, and an exogenous shell 1 illustrated in FIGS. 2 to 4. The inner boot 3 is designed to keep the foot warm and to make it possible to walk comfortably in town, at the ski restaurant or in the snow. The exogenous shell 1 is designed to rigidify this inner boot and to enable it to be introduced into a ski binding or into another piece of sports equipment. The foot and the ankle are held by the inner boot, which is provided for example with laces, and with a greater pressure by the exogenous shell when the latter is closed.

45 The inner boot 3 comprises different soft padding materials 35 ensuring thermal insulation, waterproofing and comfort. The sole of the inner boot and the reinforcing rings above the base and/or the upper can however be made of rigid synthetic materials. The inner boot is however not entirely protected by the exogenous shell 1 and must therefore be made of waterproof materials. For example, the inner boot can be made of leather, Goretex, nylon etc. with soft padding of synthetic or natural materials.

The external shell 1 is itself made of rigid synthetic material. It has a structure that is to a large extent perforated to make it lighter and to allow the inner boot to be seen.

The dimensions of the exogenous shell enable the inner boot to be inserted into or extracted from it. As is seen in FIG. 2, it comprises a sole 10, a forward part 11 of an upper capable of pivoting with respect to said sole 10 around a first articulation 110 and a rear part 12 of an upper capable of pivoting with respect to said sole 10 around a second articulation 120. In a variant embodiment, not illustrated, it is also possible for only one of the two parts of the upper to be articulated. The inner boot can be inserted into the exogenous shell respectively extracted by pivoting the forward part 11 and/or the rear part 12 of the upper, as seen in FIGS. 3 and 4. In one embodiment, the inner boot could however be extracted or inserted by pivoting only the rear part 12, with the forward part remaining in the position illustrated in FIG. 3; however, the pivoting of the forward part makes the extraction easier and further enables the height and space requirement of the exoskeleton to be reduced if it remains on the ski. Reference number 18 illustrates a reinforcement around the Achilles tendon pivoting around an axis 180 connected with the basis of the exogenous shell and which, in closed position, is fastened against the inner side of the rear part 12 of the upper by means of a tenon 182 inserted in an opening of this rear upper.

The exogenous shell 1 can be closed and tightened by means of shoe buckles, in this example two buckles 112, 113 that make it possible to tense cables holding the forward part 11 of the upper tight against the rear part 12 of the upper.

The inner boot illustrated in FIG. 5 comprises a base 31, an upper 30 and a sole 37. Reference 35 indicates padding. It is closed by means of a lace 36 with a lace-stopper 34 that enables the lace to be tensed and the lace-stopper 34 to be hooked onto a fixed point on the tongue 33.

The inner boot 3 further comprises a pivot 300 on the outer side of the ankle that enables it to be fastened to the exogenous shell. A similar pivot could also be provided on the inner side of the ankle but during use proves a hindrance for walking, so that for many types of boot it is preferable to omit it.

The exogenous shell comprises a housing 14 on the inner side of the ankle in order to accommodate this pivot. The housing is constituted by an indentation 140 in a semi-circle on the forward part 11 of the upper and of a similar indentation 141 on the rear part 12 of the upper, that come to slide in a groove 301 in the pivot 300. The housing 14 can thus be opened respectively closed by pivoting the forward part 11 of the upper and/or the rear part 12 of the upper of the exogenous shell. The pivot 300 thus constitutes a rigid fastening point between the inner boot 3 and the exogenous shell 1, capable of transmitting the forces efficiently between these two parts of the boot.

In a variant embodiment, not represented, the base 31 of the inner boot is articulated relative to the upper 30 of this inner boot around the two pivots, so as to allow a limited flexion of the upper.

FIGS. 8 and 9 illustrate two views of the sole 10 of the exogenous shell 1. As is seen in FIG. 8, the sole 10 comprises a front plate 102 and a rear plate 103 that constitute replaceable wear parts fastened under the sole. Holes 100 through the sole 10 allow water and snow that accumulates inside the exogenous shell to be evacuated.

The inner side of the sole 10 is provided with a relief pattern constituted here by ribs 101 separated by grooves and collaborating with corresponding grooves and ribs under

the sole 37 of the inner boot, in order to ensure an accurate lateral positioning of the inner boot 3 in the exogenous shell 1 and a transmission of forces between these two parts of the boot. This construction further makes it possible to ensure a constant positioning of the inner boot in the exogenous shell, even if the sole 37 becomes worn when used for walking; indeed, the bottom of the grooves under the sole 37 is unlikely to become worn, so that the vertical position of the inner boot remains unchanged even if the ribs of the sole 37 become worn.

The exogenous shell advantageously comprises a structure that is to a large extent perforated to allow the inner boot to be seen. In one embodiment, the sole of the exogenous shell is comprised of two parts that are welded, glued or mechanically assembled to one another; by varying the longitudinal fastening position, it is possible to produce soles of different shoe sizes from a single mold.

The invention claimed is:

1. A sports boot comprising:
an inner boot;
an exogenous shell, whose dimensions allow said inner boot to be inserted into or extracted from it, said exogenous shell strengthening said inner boot and allowing it to be attached to a piece of sports equipment
said exogenous shell comprising a sole and an upper, wherein the upper comprises a forward part and a rear part, said rear part having an interior surface facing into the exogenous shell, and wherein an opening is formed at the interior surface of the rear part; and
a reinforcement part provided to the interior surface of the rear part of the upper and configured to be located adjacent to an Achilles tendon, wherein the reinforcement part is articulated on an axis that is fixed and

stationary relative to the sole of the exogenous shell separately from the rear part of the upper, wherein the reinforcement part includes a tenon configured to be removably inserted into the opening such that when the exogenous shell is in a closed position, the tenon is inserted into the opening in order to fasten the reinforcement part to the rear part of the upper, and wherein said sole comprises a continuous inner relief pattern constituted by longitudinally-extending ribs separated by longitudinally-extending grooves extending continuously along an entire length of the sole, the inner boot comprising a sole with a corresponding relief pattern, so as to position laterally and vertically said inner boot in the exogenous shell.

2. The sports boot of claim 1, wherein said sole of the exogenous shell further comprises a plurality of holes configured to permit water and/or snow to be evacuated from the exogenous shell.

3. The sports boot of claim 2, wherein said plurality of holes comprises a first hole and a second hole, the first and second holes being aligned with a first groove of said longitudinally extending grooves, and said first and second holes being spaced from one another in a longitudinal direction of the exogenous shell.

4. The sports boot of claim 3, wherein said plurality of holes further comprises a third hole aligned with a second groove of said longitudinally extending grooves, and wherein the second groove is disposed laterally adjacent to the first groove.

5. The sports boot of claim 4, wherein said third hole is laterally offset from each of the first and second holes.

6. The sports boot of claim 1, further comprising a front plate removably fastened to an under surface of the sole of the exogenous shell.

7. The sports boot of claim 6, further comprising a rear plate removably fastened to the under surface of the sole of the exogenous shell, wherein the rear plate is spaced from the front plate in a longitudinal direction of the exogenous shell.

8. The sports boot of claim 1, wherein the forward part is articulated relative to the sole of the exogenous shell on a first axis, and the rear part is articulated relative to the sole of the exogenous shell on a second axis, and wherein the forward part is independently articulatable with respect to the rear part.

9. The sports boot of claim 8, said inner boot comprising a pivot protruding outwards therefrom, wherein the forward and rear parts have first and second indentations, respectively, that collectively circumscribe the pivot when the exogenous shell is in the closed position.

10. The sports boot of claim 9, wherein the pivot has a groove formed therein, wherein respective surfaces of the first and second indentations are received within the groove when the exogenous shell is in the closed position.

11. The sports boot of claim 1, wherein said forward part is articulated relative to the sole of the exogenous shell, and wherein said reinforcement part is separately articulated with respect to the forward part.

12. The sports boot of claim 1, further comprising buckles for holding said forward part of the upper and said rear part of the upper closed and tight, one against the other.

13. The sports boot of claim 1, wherein said forward part is articulated relative to the sole of the exogenous shell, and wherein said rear part is articulated relative to the sole of the exogenous shell independently from the forward part.

14. The sports boot of claim 1, wherein said rear part is behind the inner boot when the inner boot is inserted into the exogenous shell.
